Term of patent 14 years

Int. Cl. D12—09

U.S. Cl. D14—3

FIG. 1

FIG. 2

FIGURE 1 is a perspective view of a truck for dispensing ice cream or the like showing my new design as seen from the front and right side;

FIGURE 2 is a perspective view thereof as seen from the rear and right side;

FIGURES 3, 4, 5 and 6 are reduced scale elevation views thereof as seen from the right side, front, left side and rear, respectively; and

FIGURE 7 is a reduced-scale top plan view thereof.

The dominant features of the design reside in the portions shown in full lines.

This is a continuation-in-part of design application Ser. No. D. 7,323 filed June 1, 1967, and now abandoned.

I claim:

The ornamental design for a truck for dispensing ice cream or the like, substantially as shown and described.
